TELEPHONE SYSTEM

Walter Pfaff, Berlin-Zehlendorf, Germany, assignor to Siemens & Halske Aktiengesellschaft, Wernerwerk, Siemensstadt, near Berlin, Germany

Application January 2, 1937, Serial No. 118,753
In Germany February 12, 1936

9 Claims. (Cl. 179—18)

The present invention relates to a circuit arrangement for automatic telephone systems and in particular to telephone private branch exchange systems in which, when all the local connecting devices are engaged, a public exchange selector is set on a calling subscriber's line.

In such arrangements it is known for special switching means to be brought into operation in dependence upon the local devices being engaged and to receive the initiating impulse for stepping the public exchange selector and for bringing it to rest.

The invention aims at simplifying the known arrangement and achieves this in that when the local connecting devices are engaged, the impulse for advancing the public exchange selector and for bringing the same to rest is taken up exclusively by the switching means which receive the impulse for advancing the public exchange selector and bringing it to rest over another path in the event of free local connecting devices being available.

By the arrangement according to the invention special switching means for receiving the impulse for stepping the public exchange switch and bringing it to rest when the local connecting paths are engaged, are dispensed with.

One embodiment of the invention is shown in the drawing. It represents a private branch exchange system in which outgoing public exchange calls can be set up in the following manner. If there are local connecting paths, which in the present embodiment consist of call finders AS and final selectors LW, available, a relay is energized after the call finder AS has been set and the final selector LW has been set on a particular contact, which relay repeats the impulse for setting the public exchange switch AW on the calling subscriber's connection to relay R₁. Relay R₁ transmits the impulse for stepping the public exchange selector and also prepares for bringing this to rest.

If all the local connecting paths are engaged, the public exchange selector AW is set at once on the calling subscriber's line. The impulse for stepping the public exchange switch and for bringing the latter to rest is likewise received by relay R₁.

The individual switching operations are as follows: When the subscriber at station T_n takes up his receiver the following circuit is completed for the calling relay R: positive, contact 1_t, over the loop at station T_n, contact 2_t, winding I of relay R and negative. Relay R energizes. On account of the opening of contact 3_r and the

closing of contacts 4_r and 5_r the calling station T_n is characterized at the testing wiper c of the call finder AS. Contact 6_r completes the following circuit for relay GR; positive, contacts 6_r, 1_t, relay GR, and negative. Relay GR closes contact 8_{gr} so that a starting circuit is completed over positive, contacts 8_{gr} and 9_c and lead A_n over which the call finder AS is set in operation in the known manner (not shown). This stepping continues until the testing circuit is established over wiper c of the call finder AS. The circuit passes over: positive, relay C, wiper c of the call finder AS, contact 5_r, winding II of relay R, contact 4_r or contact 10_t, relay T, and negative. Relay T engages and breaks the calling circuit at contacts 1_t and 2_t. At contact 1_t the circuit is broken for relay GR. Relay T also opens contact 10_t so that the testing circuit over wiper c of the call finder AS now passes only over contact 4_r.

The subsequent impulse trains set the final selector LW on a particular contact. After the setting has been completed relays A_{n1} and P are energized over wiper c of the final selector LW. Relay A_{n1} closes contact 11_{an1} so that the following circuit is set up: positive, resistance w, contacts 12_{gr}, 11_{an1}, 13_b, winding I of relay D, winding I of relay R₁ and negative. In the above circuit only relay R₁ energizes and not relay D. Relay R₁ closes contact 14_{r1} so that the rotary magnet DAW of the public exchange selector AW is operated by relay interrupter RU. The circuit for the rotary magnet DAW passes over: positive, relay interrupter RU, contacts 14_{r1}, 15_{c5}, rotary magnet DAW and negative. Relay R₁ has also closed contact 16_{r1} and has thus prepared for bringing the public exchange selector to rest. When the public exchange selector AW has been set on the calling subscriber's line the following circuit is closed: positive, contact 16_{r1}, winding III of relay C₅, wiper d of the public exchange selector AW, lead 17, wiper d of the call finder AS, contact 18_p, relay FR, wiper d of the final selector LW, lead 19, and negative. In the above circuit relay C₅ energizes and by opening contact 15_{c5} brings the switch AW to rest.

The local link is released by relay FR and the known guarding (not shown) of the calling subscriber's line over wiper c of call finder AS is released. The following guarding circuit can now be established: positive, contacts 20_{tr}, 21_{c5}, 50 winding I of relay C₅, wiper c of the switch AW, lead 22, winding II of relay R, contact 4_r, relay T and negative. Relay C₅ energizes and switches the line through at contacts 23_{c5} and 24_{c5}. The calling subscriber receives his feeding current 55

over relay S. Relay S energizes relay VI over contact 25s. Relay VI closes contact 26v1 so that relay B also operates its contacts. Relay B opens contact 13b and closes contact 27b so that 5 a further calling impulse on the part of a subscriber again operates on the relay R1 of the public exchange selector AW shown, but is transmitted over contact 27b to the second public exchange selector. Relay S can receive the 10 pulses for setting the public exchange connecting devices and repeats them over the public exchange line at contact 28s.

If all the local connecting devices are engaged all the C relays of the call finders serving the 15 local traffic are energized. Thus the chain over contacts 29c, 30c1, etc., is completed. If now when all the local connecting devices are engaged the private branch exchange subscriber takes up his receiver the calling relay R and in consequence 20 relay GR become energized in the manner described. Relay GR establishes the following circuit: positive, contacts 8gr, 29c, 30c1, 31ab, 32an1, 13b, winding I of relay D, winding I of relay R1 and negative. Relay R1 completes the 25 circuit for the rotary magnet DAW in the manner already described and prepares for bringing the public exchange selector to rest by closing contact 16r1. When the public exchange selector AW is set on the calling subscriber's line the 30 testing circuit passes over: positive, contact 16r1, winding III of relay C5, wiper d of the switch AW, lead 17, contacts 33t, 57, winding II of relay R, contact 47, or 10t, relay T, and negative. Relay T energizes and as already described breaks 35 the calling circuit and the circuit for relay GR. The public exchange selector is brought to rest by relay C5 through the opening of contact 15c5 and the guarding circuit is set up over contact 21c5. At the same time the line is switched 40 through at contacts 23c5 and 24c5.

As may be seen from the foregoing description, special switching devices for setting the public exchange selector on a calling subscriber's line in the event of all the local connecting devices 45 being engaged are absolutely unnecessary.

When the impulse for setting the public exchange selector, in the event of all the local connecting paths being engaged, is received by relay R1, relay D energizes. Relay D locks up over: 50 positive, contacts 34c5, 35d, winding II of relay D and negative. By opening contacts 36d and 37d and closing contacts 38d and 39d dial tone w2 is applied to the speaking leads to inform the calling subscriber that he can commence to dial.

55 This dial tone may be different from the usual dial tone so that the calling subscriber is thereby informed that he has been connected to a public exchange line.

When the subscriber dials the number of outgoing calls the impulses transmitted from the subscriber at station Tn are received by relay S and then repeated to the rotary magnet DML. The circuit for magnet DML passes over: positive, contacts 40v1, 41s, rotary magnet DML and negative. Through the impulse train, relay V2 is engaged over: positive, contacts 42s, and 43v1, relay V2 and negative. When at the end of the impulse train relay V2 releases the following circuit is established provided that the digit characterizing outgoing public exchange calls has been 60 dialled: positive, contact 44v2, wiper a of the switch ML in the position corresponding to the characterizing digit for outgoing public exchange calls, lead 45, contact 46d, winding III of relay D, winding II of relay D and negative. Winding III

of relay D is arranged so as to oppose the effect of winding II so that relay D is caused to release by means of the counterwinding III. Relay D opens contacts 38d and 39d. This switches the public exchange line through.

If the subscriber dials a digit other than the digit for outgoing calls wiper a of the switch ML passes to a position in which winding III of relay D is not connected up. Relay D then remains energized and prevents the public exchange line from being switched through at contacts 36d and 37d. The subscriber receives the signal telling him that for the time being all the local connecting paths are engaged. The calling subscriber replaces the receiver and thereby 15 causes the devices which have been taken into use to be restored. The public exchange selector AW is restored to normal in the known way through the release of relay S. Relay C5 de-energizes and completes a circuit over: positive, 20 relay interrupter RUI, contact 47c5, wiper b of the switch ML in the working position, rotary magnet DML and negative. The rotary magnet DML is operated until the switch ML reaches the normal position. Thereupon all the switches 25 which have been taken into use are once more in the normal position. The arrangement could also be modified by connecting the points 48/48 so that after a digit other than that characterizing public exchange calls has been dialled a relay TR 30 is energized over wiper a of switch ML and the multiple connected empty contacts, which relay by opening the guarding circuit at contact 20tr brings about the release of relay C5 and thus releases the public exchange selector AW. 35

What is claimed is:

1. In a private branch telephone system wherein a main exchange selector connects with a calling line when all local connecting lines are busy, switching means associated with said selector, means including all of said busy connecting devices for preparing said switching means for operation, said switching means operated thereafter responsive to an impulse transmitted by the initiation of an additional call to start 45 said selector stepping to find the calling line and for preparing a stop circuit for terminating the stepping of said selector when the calling line is found, and means responsive when a connecting device is idle and a trunk call is initiated thereover by a calling subscriber for transmitting an impulse to operate said switching means to control said selector in identical manner.

2. In a system as claimed in claim 1, in which said switching means includes a relay operated 55 by an impulse transmitted by the initiation of a call when all of said connecting devices are engaged or when a trunk call is extended over an idle connecting device.

3. In a system as claimed in claim 1, a testing circuit for said selector including a wiper thereof, said testing circuit testing for a calling line as the wipers of said selector are advanced and completing the stop circuit to terminate the stepping of said selector when the calling line is 65 found, said testing circuit being identical for finding a calling line when idle connecting devices are available or when all of said connecting devices are engaged.

4. In a private branch telephone system where- 70 in a main exchange selector connects with a calling line when all local connecting devices are busy, switching means for starting said selector stepping, means including all of said busy connecting devices for preparing said switching 75

- means for operation, a calling subscriber's line equipment, means controlled by said line equipment when a call is initiated at a time all of said connecting devices are busy for transmitting an impulse for operating said switching means, and a testing circuit including a wiper of said selector and said line equipment for terminating the stepping of said selector when said calling line equipment is found.
5. In a private branch telephone system where-in a main exchange selector connects with a calling line when all local connecting devices are busy, switching means for starting said selector stepping, means including all of said busy connecting devices for preparing said switching means for operation, a calling subscriber's line equipment, means controlled by said line equipment when a call is initiated at a time all of said connecting devices are busy for transmitting an impulse for operating said switching means, a testing circuit including a wiper of said selector and said line equipment for terminating the stepping of said selector when said calling line equipment is found, means responsive 10 when any one of said connecting devices are idle and a call is initiated for controlling said idle connecting device to find the line equipment of said calling line, means controlled by said calling subscriber for controlling said connecting 15 device to initiate a trunk call, means operated responsive to the initiation of a trunk call for transmitting an impulse for operating said switching means, said testing circuit now including a wiper of said selector and said connecting device for terminating the stepping of said selector when said calling line is found.
6. In a system as claimed in claim 1, a register in said selector, a special relay, said special relay included in series with said switching means and operated in series therewith only when all of said connecting devices are busy when an additional call is initiated, and means controlled by the operation of said special relay for placing said register under control of the calling line.
- 45 7. In a private branch telephone system where-in a main exchange selector connects with a calling line when all local connecting devices are busy, switching means associated with said selector, a special relay included in series with said switching means, means including all of said busy connecting devices for preparing said switching means and said special relay for operation, said switching means and said special relay operated in series thereafter responsive to an impulse transmitted by the initiation of a call by a subscriber, means controlled by the operating of said switching relay for starting said selector stepping to find the line of the subscriber initiating said call and for preparing a stop circuit for terminating the stepping of said selector when a calling line is found, a register associated with said selector, means controlled by the operation of said special relay for connecting said register to said selector, a trunk line to a public exchange terminating in said selector, means in said selector controlled by said calling subscriber for setting said register, and means controlled by the setting of said register for either extending said calling line through to said trunk line by way of said selector or for preventing the extension of said calling line to said trunk line.
8. In a system as claimed in claim 7, in which a release relay is provided for said selector, said release relay operated responsive to the setting of said register to a position other than the position determining a trunk call to restore said selector to normal.
9. In a telephone system, subscribers' lines, a plurality of connecting devices controllable by said calling subscribers to extend local connections, a trunk line to a distant exchange, a selecting device having access to said subscribers' lines terminating said trunk line, switching means associated with said selecting device, a chain circuit for preparing said switching means for operation when all of said connecting devices are engaged, means for operating said switching means to start said selecting device stepping to find a calling subscriber's line responsive to an impulse transmitted over said chain circuit by the initiation of an additional call, means in said selecting device operated responsive to the finding of the calling line for terminating the stepping thereof, and means in said selecting device controlled by said calling subscriber for extending a connection over said trunk line.

WALTER PFAFF.
